United States Patent

Des. 238,686

Patented Feb. 3, 1976

238,686

ASH COLLECTOR

William F. Martin, 350 Stonycroft Road,
Ridgewood, N.J. 07450

Filed Feb. 21, 1974, Ser. No. 444,269

Term of patent 14 years

Int. Cl. D27—03

U.S. Cl. D27—14

FIG. 1

FIG. 2

FIG. 3

FIG. 1 is a front elevational view of an ash collector;
FIG. 2 is a rear elevational view; and
FIG. 3 is a right side elevational view, the left side
being a mirror image thereof.

I claim:

The ornamental design of an ash collector, as shown
and described.
